UNITED STATES PATENT OFFICE.

RUDOLPH STAUDINGER, OF BROOKLYN, NEW YORK.

DESIGN FOR A CANISTER.

SPECIFICATION forming part of Design No. 19,141, dated June 4, 1889.

Application filed May 1, 1889. Serial No. 309,292. Term of patent 7 years.

To all whom it may concern:

Be it known that I, RUDOLPH STAUDINGER, a citizen of the United States, residing at Brooklyn, in the county of Kings and State of New York, have invented and produced a new and original Design for a Canister, of which the following is a specification, reference being had to the accompanying drawing.

The drawing represents a perspective view of my canister.

The leading feature of my design consists of a globe resting upon curved legs and of a streamer extending across the globe and arranged in graceful curves.

In the drawing, the letter A designates the body of my canister, which is made in the form of a hollow globe the surface of which is marked with parallel lines *a a* and with meridian-lines *b b*.

B is the lid which fits an opening in the top of the globe, and the lower edge of which coincides with one of the parallel lines *a*. The

globe is provided with curved legs *C C*, the bottom ends of which are made in the form of rings *c c*. Between the legs *C C* protrudes ²⁵ the spout *D*, the gate *d* of which is provided with an ornamental handle *d'*.

The surface of the globe *A* is ornamented by a streamer *E*, which is arranged with graceful folds *e e*.

What I claim as new, and desire to secure by Letters Patent, is—

The design for a canister herein shown and described, the same comprising the globe *A*, the curved legs *c c*, and the streamer *E*, with ³⁵ its folds *e e*, as set forth.

In testimony whereof I have hereunto set my hand in the presence of two subscribing witnesses.

RUDOLPH STAUDINGER.
